FIG. 4.

UNITED STATES PATENT OFFICE

CHARLES KOLODNY, OF BROOKLINE, MASSACHUSETTS

CARD TABLE

Application filed March 1, 1930. Serial No. 432,427.

This invention relates to new and useful improvements in tables and more particularly to card tables of the bridge type, the primary object of the invention being to provide a table of this type which is constructed with drawers at each side so that all players may have a convenient place to dispose of cigarettes, ashes and personal effects without interfering with the playing surface of the table.

A further object of the invention resides in the provision of improved means for supporting the drawers in the sides of the table and further in the construction of a top and support for the drawers which will not interfere with close seating of the players at the table.

A still further object of the invention resides in providing a table of the character mentioned which is simple and durable in construction, comparatively inexpensive to manufacture and one which will be very efficient and useful in operation.

With these and other objects in view, my invention consists in the novel features of construction, combination and arrangement of parts as will be hereinafter referred to and more particularly pointed out in the specification and claim.

In the accompanying drawings, forming a part of this application;

Figure 1 is a perspective view of a table constructed in accordance with my invention with two of the drawers disposed to withdrawn position;

Figure 2 is a bottom plan view of the table with the legs folded and two of the drawers disposed to withdrawn or extended position, parts of one of the drawers being cut away;

Figure 3 is a transverse section as seen on the line 3—3 of Figure 2; and

Figure 4 is a fragmentary detail section taken through one of the drawers in closed position with the leg in extended or upright position.

One of the greatest objections to the present-day card tables of the bridge type seems to be the lack of facilities to support therein or therein ash trays, or other personal equip-

ment necessarily used during the course of a game by the players. I realize that attachments have been made and sold for use in connection with a bridge table to support ashes, for instance, but these are not entirely satisfactory to players since they interfere with clean surface of the table top. Moreover, anything placed on the top of a small bridge table becomes an obstruction and either interferes with the play or the players. Ordinarily drawers are not applied to a bridge table because the ordinary construction of such a table would not permit thereof and further it has been felt that the use and application of a drawer in connection with such a table would interfere with the proper seating of the players for comfort at such a table. I have discovered a new means of constructing a bridge table with drawers, as will appear from the following description as disclosed in the accompanying drawing.

In describing the invention, I shall refer to the drawings in which similar reference characters designate corresponding parts throughout the several views and in which 1 designates the table top formed of any preferred material and of the usual or any desired size, the same being adapted to be covered with any desired material. Applied to the under face of the top 1 to fit flush with the edges of said top and secured to the latter in any preferred manner are the four strips 2 and applied to the outer face of the strips 2 to project slightly beyond the edges of the top 1 are the outer strips or plates 3. Secured to each strip 2 adjacent one end thereof is an angle bracket 4, the same being held by the last mentioned strip by means of a set screw 5, the opposite angle face of the bracket being spaced from the adjacent strip 2 and supported on the latter by means of a bolt 6, said bolt forming a pivot for the leg 7. The legs are braced in the usual or any preferred manner such as by means of the bracing members 8.

As shown in Figure 1 and Figure 2, the strips 2 and adjoining plates 3 are arched centrally, said arching being designated by 100

the numeral 9. This permits of the players being seated closely to the table.

Secured to the under face of the bottom 1 in any preferred manner and extending inwardly from each strip 2 from a point nearer one end thereof is a bar 10, the bar from each strip 2 abutting at its innermost end the side of the bar extending from the succeeding strip 2 and secured thereto. This securing of the bars which intercept one another is by means of the nail 11 shown in dotted lines in Figure 2. These intercepting bars 10, obviously, form braces for the side strips 2 and said bars are each cut out or grooved at one end as shown at 12 to receive therein the legs 7 when the latter are disposed to folded position, as clearly shown in Figure 2 of the drawings.

The primary purpose of these bars 10 is to form means whereby drawers may be supported readily and simply in the table. To this end, one face of each of the bars 10 is grooved at the top thereof from its outer end inwardly a predetermined distance, the grooves of said bars being designated by the numeral 13. The inner face of each strip 2 opposing the adjacent bar 10 is similarly grooved as shown at 14. Fitting in an opening 15 formed in each side of the table adjacent one end thereof, that is, formed in the strips 2 and abutting plates 3 in registration with said grooves, is a drawer 16. This drawer obviously fits under the top 1 and operates in the grooves 13 and 14, the same being divided by partitions 17 to form compartments therein so as to contain smoking equipment, cards or the personal equipment of the players. Any form of handle 18 may be provided on the drawers to enable the same to be readily withdrawn or extended. When the drawer is disposed to its closed position the front face thereof will fit flush with the outer plate 3, as clearly shown in Figure 4 of the drawings. Such drawers disposed toward one end of the side of the table where the player is seated will not interfere with the seating of said player and it will be seen that the same will form a great convenience to the player and add materially to the efficiency and usefulness of the table.

While I have described the elements best adapted to perform the functions set forth, it is obvious that various changes in form, proportion and the minor details of construction may be resorted to without departing from the spirit or sacrificing any of the principles of the invention.

Having thus described my invention, what I claim is:

In a table, a top, depending side strips for said top extending along marginal portions thereof, bracing bars against the under face of the top in parallel spaced relation to the side strips and each having its outer end

secured against a side strip in spaced relation to an end thereof and its inner end secured against a side face of a companion bracing bar transversely thereof in spaced relation to its ends, a recess being formed in the under face of each bracing bar at its outer end, a bearing bracket carried by each side bar and projecting from the inner side face thereof in spaced relation to an intersecting side strip, supporting legs pivoted between the side strips and brackets and when folded extending longitudinally of the side strips with their free end portions overlapping the bracing bars and engaged in the recesses formed therein, each side strip having an opening formed in one end portion thereof and the side strips and bracing bars having their confronting faces formed with grooves constituting tracks leading inwardly from opposite sides of the openings, and drawers engaged through the openings and slidably supported upon said tracks.

In testimony whereof I affix my signature.

CHARLES KOLODNY.
